(57) **CLAIM**

The ornamental design for pectus carinatum brace, as shown and described.

DESCRIPTION

FIG. 1 is a perspective view of a pectus carinatum brace showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof shown with an example of environment in use.

The broken lines in the drawings illustrate portions of the pectus carinatum brace and its environment and form no part of the claimed design.
